[57] CLAIM

The ornamental design for a microwave detector, substantially as shown and described.

DESCRIPTION

FIG. 1 is a perspective view of a microwave detector showing my new design;
FIG. 2 is a front elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a rear elevational view thereof;
FIG. 8 is a perspective view of the microwave detector of FIG. 1 with the cap omitted for ease of illustration;
FIG. 9 is a front elevational view of FIG. 8;
FIG. 10 is a left side elevational view of FIG. 8;
FIG. 11 is a right side elevational view of FIG. 8;
FIG. 12 is a top plan view of FIG. 8;
FIG. 13 is a bottom plan view of FIG. 8;
FIG. 14 is a rear elevational view of FIG. 8.
